PACKAGING MACHINE

Charles F. Richard, Battle Creek, Mich., assignor
to Johnson Automatic Sealer Co., Ltd., Battle
Creek, Mich., a partnership-association limited
of Michigan

Application November 7, 1931, Serial No. 573,699
Renewed January 24, 1935

36 Claims. (Cl. 93—6)

This invention relates to packaging machinery, and more particularly to machines for closing the top of a liner or bag of a lined carton prior to the closing and sealing of the carton itself.

5 One of the objects of the present invention is to provide new and improved mechanism for automatically closing in a rapid and efficient manner the tops of the liners or bags of a succession of lined cartons as they pass through a packaging machine.

10 Another object is to provide a carton sealing machine for cartons having inner bags or liners with novel means for automatically folding and sealing the open tops of said bags or liners prior to the sealing of the cartons themselves.

15 A further object is to provide mechanism of this character wherein the folding of the liner top is progressively accomplished by means of a succession of folders of novel construction, while the sealing thereof is effected by the application of heat to the folded portion.

20 Still another object is to provide novel automatic mechanism for spreading the open end of the filled liner of a carton and for neatly folding said end so as to effectively seal the liner against loss of its contents.

25 A still further object is to provide automatic folding and sealing mechanism for closing the open ends of carton liners made of a self-sealing material, embodying novel means for continuously heating both the folding and sealing elements thereof.

30 Another object is to provide an improved packaging machine through which a carton having a filled inner bag or liner is automatically advanced, the material in the liner being packed below the score lines of the carton flaps, the open end of the liner being spread, closed, folded and sealed, and the flaps of the carton itself being closed and sealed, all of said operations taking place successively as the carton is continuously advanced through the machine.

35 A further object is to provide a packaging machine for handling lined cartons embodying novel mechanism for folding and sealing the liners, and including means for folding down and maintaining the flaps of the cartons out of the path of said liner folding and sealing mechanism until said operations are completed, and additional means for then folding said carton flaps over into sealing position.

40 These and other objects will appear more fully from a consideration of the detailed description of the invention which follows. Although only one

embodiment of the invention has been described and illustrated in the accompanying drawings, it is to be expressly understood that these drawings are for the purpose of illustration only and are not to be construed as a limitation of the scope 5 of the invention, reference being had for this purpose to the appended claims.

In the drawings, wherein like reference characters indicate like parts throughout the several views:

10 Figs. 1 and 1a, when joined along the broken lines, constitute a plan view of a packaging machine forming one embodiment of the present invention;

15 Figs. 2 and 2a, when joined along the broken lines constitute a side elevation of the machine disclosed in Figs. 1 and 1a.

20 Fig. 3 is an end view, taken from the right of Figs. 1a and 2a, with certain parts omitted for the sake of clarity;

25 Fig. 4 is a sectional view taken substantially on the line 4—4 of Fig. 1a;

Fig. 5 is a plan view on an enlarged scale of the fixed folder mechanism, with certain parts omitted for the sake of clarity;

30 Fig. 6 is a side elevation of the right-hand (as viewed from the right of Fig. 5) set of fixed folders;

35 Figs. 7, 8, 9, 10 and 11 are sectional views through the fixed folders taken substantially on lines 7—7, 8—8, 9—9, 10—10, and 11—11, respectively, of Fig. 5.

Fig. 12 is a section through the heated sealing means taken substantially on line 12—12 of Fig. 1;

40 Fig. 13 is a sectional view through the last set of fixed folders taken substantially on the line 13—13 of Fig. 1;

Fig. 14 is a sectional view through the mechanism for striking up the end flaps of the carton taken substantially on line 14—14 of Fig. 1; and

45 Figs. 15 and 15a, when joined along the broken lines, constitute a diagrammatical representation in perspective of the various flap and liner spreading, liner folding and end flap folding means of the present invention, including a representation of the condition of the carton and liner top at each step during its progress through the machine.

50 Referring now to the drawings, there is disclosed therein a novel machine for folding and sealing the tops of the liners or inner bags of lined cartons, and for folding in the end flaps of the tops of said cartons themselves prior to the closing and sealing thereof. In this machine,

cartons containing open topped, filled liners of a self-sealing material such as waxed paper, are supplied to the receiving end thereof from any suitable source, such as a filling and weighing machine, by means of a suitable conveyor. From the conveyor the open cartons are transferred by suitable pusher means to a carrier mechanism traversing the length of the liner folding and sealing machine, which mechanism may, if desired, constitute an extension of the carrier mechanism of any of the well known carton top sealing machines. The package is then carried forward past a packing and carton flap spreading device which packs the material within the liner below the score lines of the top of the carton and simultaneously spreads the two side flaps of the carton so as to allow them to be readily moved to positions in which they will not interfere with the operations to be performed on the top of the liner. The package next passes beneath a liner spreading mechanism which spreads the liner top longitudinally, or in the direction of movement of the carrier means, and travels with the carton for a predetermined distance while the first fold or crease is made in the liner by means of a pair of folder arms disposed on opposite sides of the liner top and movable together transversely to the direction of movement of the carton for bringing together the opposite sides of the liner top and thereby forming a fold or crease therein at substantially the level of the carton flaps.

As the carton is advanced further through the machine, the liner top passes between a plurality of fixed folder members which are so shaped and provided with suitable grooves that the liner top is doubled over upon itself a plurality of times so as to form any desired number of additional folds therein. The folded liner top is then moved between a pair of suitable heated sealing members which effectively seal the liner top by melting the wax or other suitable substance with which the liner is treated. Further advance of the carton through the machine passes the folded and sealed liner top through another set of fixed folders which flatten the liner top to substantially the level of the score lines of the carton flaps, whereupon a pressure plate engages the top of the liner and the carton side flaps while fingers raise or strike the carton and flaps into position so that suitable means may fold them in on top of the folded and sealed liner. From this point, the carton may be delivered to any desired form of top sealing machine such as that disclosed in Patent No. 1,118,424, issued November 24, 1914 to Harry L. Johnson.

Referring now more particularly to Figs. 1, 1a, 2, and 2a, a machine embodying the present invention is disclosed therein as being mounted on and supported by a pair of laterally spaced side frames 16 and 17 of any suitable construction which are supported above the floor or machine foundation by suitable legs 18 and which, if desired, may be formed as the extensions of the side frames of a carton top sealing machine such as that disclosed in Patent No. 1,118,424. Side frames 16 and 17 may also be rigidly connected together by suitable cross tie members 19, 19', 19'', and 19'''.

The various component elements of the folding and sealing machine forming the subject matter of the present invention are mounted on and supported by the framework just described, and suitable carrier means are provided for moving lined and filled cartons the length of the machine past the various folding and sealing devices. In

the form shown, the carton advancing or carrier means comprises an extension of the carrier of the top sealing machine to which the present machine is connected, and includes a plurality of carton engaging pusher members 20 adjustably secured as by suitable brackets 21 to an endless conveyor chain 22 which passes around a suitable sprocket 23 mounted on a shaft 24 journaled adjacent the receiving end of the liner folding and sealing machine, and a similar sprocket (not shown) at the delivery end of the carton top sealing machine. Chain 22 and the pusher members 20 mounted thereon may be driven in any suitable manner from the main driving shaft of the carton top sealing machine. A conveyor way 15 is arranged above the conveyor chain 22 and preferably comprises a pair of horizontal bottom pieces 25 (Fig. 3), on which the cartons are adapted to be supported and between which brackets 21 project, and vertically spaced side 20 pieces or guides 26, both said bottom and side pieces being secured to suitable uprights 27 which may in turn rest upon the floor or machine foundation. As is shown best in Fig. 1a, the side pieces or guides 26 on one side of the carrier means at the receiving end thereof are shorter than those on the other side, and the bottom piece 25 of the conveyor way on that side of the carrier is extended laterally to provide a transfer table 28 over which lined and filled cartons may be moved in being transferred to the carton carrier or advancing means from the means which supply the filled cartons to the liner folding and sealing machine.

In the form shown, the lined and filled cartons 35 are supplied by means of a continuously moving conveyor 29 of any suitable construction, said conveyor terminating adjacent the receiving end of the carrier means of the liner folding and sealing machine and in such a location as to permit transfer of the cartons to said carrier means by suitable pusher mechanism such as that disclosed in Figs. 1a, 2a, and 3. As therein shown, the lined and filled cartons C, open at the tops, are advanced by conveyor 29 until they abut a pair 45 of combined stop and guide members 30 suitably secured to side frame 16 and extending transversely across conveyor 29 to the side of the carrier means on which side pieces or guides 26 are broken away. As the cartons abut stop members 30 they are in alignment with transfer table 28 and with an L-shaped pusher member 31 which is adapted to be reciprocated by suitable means to transfer the cartons from conveyor 29 across transfer table 28 onto bottom members 25 of the conveyor way, in position to be engaged by a pusher member 20. During this transfer, the transverse arm of L-shaped pusher member 31 serves to maintain the next carton on conveyor 29 in place until pusher member 31 completes its 60 reciprocation and is ready to transfer another carton.

Although any suitable means may be provided for reciprocating pusher member 31, it is desirable that the operation of said member be synchronized with the movements of carrier chain 22 and pusher members 20, and the other elements of the liner folding and sealing machine later to be described. Accordingly, pusher member 31 is secured to and carried by a suitable bracket 32 which may be formed integrally with a sleeve 33 slidably mounted upon a shaft 34, the latter being mounted transversely of the machine and supported in suitable bearings 35 secured to side frames 16 and 17. Adjustably connected 75

to sleeve 33 is a rack 36 which is in engagement with and reciprocated by a gear 37 rotatably mounted on and supported by a stub shaft 38 which is secured in and depends downwardly from cross tie member 19. Secured to, and preferably formed integrally with, gear 37 is a pinion 39 which meshes with and is driven by a gear 40 secured to one end of a stub shaft 41 journaled in cross tie member 19. To the other end of stub shaft 41 is secured an arm 42 which, through a suitable connecting rod 43, is connected to one end of a bell crank 44 (Figs. 1 and 2). Bell crank 44 is pivotally mounted in any suitable manner on side frame 17 and is adapted to be reciprocated about its pivot by the action of a cam roller 45 mounted on the end of said bell crank opposite to connecting rod 43 and in engagement with the cam groove of a cam 46 which is mounted on and continuously rotated by a shaft 47 extending transversely of the machine and supported in suitable bearings mounted on side frames 16 and 17.

Shaft 47 is the main drive shaft of the liner folding and sealing mechanism, and is adapted to be continuously rotated in any suitable manner, as by a chain or belt drive (not shown) from the main driving shaft of the carton top sealing machine to which the liner folding and sealing machine is connected. Also, the rotation of main driving shaft 47 and the movement of conveyor chain 22 of the carrier means are synchronized and preferably controlled by a common switch (not shown).

After a carton has been transferred by pusher member 31 from conveyor 29 across transfer table 28 and onto bottom pieces 25 of the conveyor way, its rear face is engaged by one of pusher members 20 and the carton is advanced through the machine, side pieces or guides 26 acting to maintain the cartons vertical and centered on the conveyor way against any tendency to laterally displace them. As the lined and filled carton open at the top is thus advanced, it approaches mechanism which has been provided for packing the material in the carton liner below the score lines of the carton flaps and for spreading the side flaps of the carton top.

In the form shown, a shaft 48 is mounted transversely of the machine in a position well above the plane of the tops of the cartons and is rotatably supported in suitable bearings 49 secured to the tops of side frames 16 and 17. Shaft 48 is adapted to be driven in synchronism with the carrier means and the other elements of the machine as by a chain 50 which encircles sprockets 51 and 52 mounted on main driving shaft 47 and shaft 48, respectively. Mounted on and secured to shaft 48 by means of a sleeve 53, directly above the path of travel of the carton being advanced by the carrier means, is a combined packing and flap spreading member 54. As shown best in Fig. 15a, packing and flap spreading member 54 comprises an irregularly curve-shaped packing body 55 which may be made hollow in order to conserve weight and secured to sleeve 53 as by a web 56, and laterally extending flap guide members or fins 57 which may be made integral with packing body 55, or otherwise suitably secured to shaft 48. The width of packing body 55 is such as to allow it to freely enter between the sides of the liner of a carton, and its irregularly curved shape is such as to permit said body to penetrate down into the liner and properly pack the material therein below the score lines of the carton top.

Flap guide members or fins 57 extend beyond the sides of packing body 55 a sufficient distance to insure engagement with the inner surfaces of the sides of the liner top and thereby exert an outward pressure against the side flaps of the carton top so that the latter may be spread prior to the folding of the liner top. The direction of rotation of shaft 48 is clockwise, as viewed in Figs. 2a and 15a, so that when packing body 55 is in engagement with the material within the liner it is moving in the same direction as the carton.

As the side flaps of a carton are spread by flap guide members 57 of the rotating packing and flap spreading member 54, the pointed ends 58 of a pair of flap guide rails 59 enter between the side flaps of the carton and the vertical sides of the liner top, and, due to their downwardly and outwardly curving construction, put said side flaps down to a substantially horizontal plane 20 level with or slightly below the score lines of the carton top and hold them in that position until after the carton has advanced through the machine to the fixed folder mechanism later to be described, whence the side flaps are held down by certain elements of said mechanism.

Leaving the packing and side flap spreading mechanism, the cartons are advanced to a position below mechanism which is provided for spreading the tops of the liners longitudinally, or in the direction of movement of the carrier means, preparatory to making the first fold or crease therein. As shown in Figs. 1a, 2a, and 4, suitable liner spreading mechanism may comprise a raceway framework 60 supported in a vertical plane directly over the path of travel of the cartons by a pair of supporting bracket members 61 which are secured at their outer ends to frame members 16 and 17 and extend transversely thereto across the machine with raceway 40 framework 60 suitably secured to their inner ends. Mounted in suitable bearings 62 at one end of raceway framework 60 is a shaft 63 on which is secured a sprocket 64. A similar sprocket 65 is secured to a shaft 66 rotatably mounted in bearings 67 adjacent the opposite end of raceway 60, and a suitable chain 68 passes around both sprockets 64 and 65. Mounted on and detachably secured at intervals along chain 68 are a plurality of travelling carriers 69 on each of which is suitably mounted a pair of spreader members 70 and 71. Spreader members 70 and 71, which are shown as being made of hard rubber or other similar material, although they may comprise brushes of hair or the like, are pivotally mounted on carriers 69, and, while the latter are continuously moved around raceway 60, are adapted to penetrate into the open top of a carton liner and then to be separated or spread apart so as to spread the liner longitudinally in its direction of travel, the spreader members continuing to travel with the liner for a predetermined distance until the first fold has been made therein. The continuous movement of chain 68 upon which carriers 69 are mounted is derived from main drive shaft 47 through a driving sprocket 72 secured to the latter, a driven sprocket 73 secured to shaft 66, and a suitable driving chain 74 encircling both sprockets 72 and 73.

In the embodiment shown, the means for pivotally mounting spreader members 70 and 71 and for separating them after they have penetrated the open top of a liner preferably comprises a pair of shafts 75 and 76 rotatably supported in

suitable bearings transversely of carrier 69 and a pair of arms 77 and 78 secured to shafts 75 and 76, respectively, intermediate the ends thereof and in the same vertical plane as the center line of the carrier mechanism which advances the cartons through the machine. Spreader members or brushes 70 and 71 are removably secured in any suitable manner to the extremities of arms 77 and 78, respectively. Arms 77 and 78, and their attached spreader members 70 and 71, are normally resiliently urged to the positions occupied by those elements which are shown secured to the uppermost carried in Fig. 2a. Arm 77 is resiliently urged to this position by a spring 79 one end of which is fixedly secured to the carrier 69 as at 80 while the other end is fastened to a pin 81 which is secured to shaft 75, thereby tending to rotate said shaft in a counter-clockwise direction. A suitable stop member 82 is provided to limit the counter-clockwise movement of arm 77. Arm 78 is likewise resiliently urged to the position shown by means of a coil spring 83 which is wrapped around a portion of shaft 76 and has one end secured to said shaft while the other end is fastened to carrier 69.

As carrier 69, with its arms 77 and 78 and spreader members 70 and 71 in the positions described, is continuously moved in a clockwise direction, through the driving connections described, it approaches the rear end of raceway 60 to which is adjustably secured on one side thereof a substantially U-shaped cam plate 84. As carrier 69 is carried around the end of raceway 60, a cam roller 85 carried by an arm 86 secured to one end of shaft 75 comes into engagement with cam plate 84, and, due to the shape thereof, rotates shaft 75 and moves arm 77 in a clockwise direction so as to point substantially vertically downward. Since chain 68 upon which carriers 69 are mounted derives its movement from main driving shaft 47, the movement of the carriers is synchronized with that of the carton carrier or advancing means, and spreader member 70 carried by arm 77 is assured of ready penetration into the open top of a carton liner.

Chain 68 of the liner spreading mechanism and carriers 69 are not only moved in synchronism with the carton advancing means, but are also moved at the same speed therewith. Accordingly, further movement of carrier 69 around the rear end of raceway 60 and then along the bottom side thereof introduces spreader member 71 into the open top of the same liner into which spreader member 70 has already penetrated, arm 78 and spreader member 71 still maintaining their normal position which is substantially at right angles to carrier 69. Further movement of carrier 69 forward along the bottom of raceway 60, and now in company with one of the cartons, brings a cam roller 87, which is carried by an arm 88 secured to one end of shaft 76, into engagement with an upwardly inclined cam plate 89 which may be suitably supported from one of supporting bracket members 61. Engagement of cam roller 87 with cam plate 89 rotates shaft 76 and its attached arm 78 and spreader member 71 in a counter-clockwise direction and thereby separates or spreads the latter from spreader member 70 so as to spread or elongate the liner top in its direction of travel.

Spreader members 70 and 71 maintain this separated position during the travel of carrier 69 along the bottom of raceway 60 for a distance

equal to the horizontal portion of cam plate 89 shown in Fig. 2a, during which time the front and rear end flaps of the carton are put down and the first fold or crease is made in the liner top by mechanism later to be described. As carrier 69 approaches the front end of raceway 60, roller 87 passes off of cam plate 89, spreader members 70 and 71 pass out of the liner top, and arms 77 and 78 are returned to their original positions by springs 79 and 83.

Referring now to the mechanism for putting down the front and rear end flaps of the carton and for making the first fold or crease in the liner top, which mechanism operates substantially concurrently with the liner spreading means just described, the rear end flap is put down even with the score lines of the carton top by a pair of flap engaging guides 90 and 91 (Figs. 1a, 2a, and 15a) curved upwardly at their rear ends and secured to the ends of a pair of arms 92 and 93 which are in turn rigidly mounted on a pair of stub shafts 94 and 95 journaled in suitable bearing brackets 96 supported by side frames 16 and 17. Stub shafts 94 and 95 are also provided with arms 97 and 98 secured at one end thereof to said shafts and carrying at the other end adjustable cam rollers 99 and 100. These cam rollers are maintained in engagement with the surfaces of a pair of similar cams 101 and 102 by suitable resilient means such as springs 103 fastened at one end to arms 97 and 98 and at the other end to side frames 16 and 17. Cams 101 and 102 are mounted for rotation with shafts 104 and 105 which are suitably journaled in bearing brackets 106 and 107 secured to and extending inwardly from side frames 16 and 17.

Shafts 104 and 105, which also form part of the movable first folder or creasing mechanism later to be described, derive their movements through suitable chain and gear transmissions from main driving shaft 47, and hence are synchronized with the other movable elements of the machine. Flap bending guides 90 and 91 are fixed in such positions on arms 92 and 93, and the relative positions of arms 92, 93, 97, and 98 and the form of cams 101 and 102 are such that the upwardly curved rear ends of guides 90 and 91 move inwardly toward one another in time to engage the upstanding rear end flap of a carton, and as the carton is advanced below said guides, the latter continue to move toward one another and to force the rear flap down at least to the level of the score lines of the carton top. After the carton flap passes from beneath guides 90 and 91, continued rotation of cams 101 and 102 permits the guides to be separated from one another under the action of springs 103 so as to allow the next carton top to pass therebetween until it is in position for the rear end flap to be engaged and bent downward.

Referring now to the means for making the first fold or crease in the liner top, a pair of elongated folder arms, preferably slightly longer than the liner tops after elongation, are provided one on each side of the line of travel of the liner tops together with mechanism for moving said arms toward and away from one another transversely to said line, said movement of the folder arms also having a component in the direction of movement of the liner tops. In the form shown, a pair of elongated folder arms 108 and 109 are secured to, and preferably formed integral with, webbed folder frames 110 and 111, respectively, and are supported thereby on opposite sides of the path of the liner tops. means are provided for giving folder arms 108 and 109 a continuous oscillatory movement toward and away from one another so as to engage the liner top between them and make the first fold or crease therein, said means comprising, in the present embodiment, a well known form of parallel motion mechanism. As shown, folder frames 110 and 111 are provided with suitable links 112 and 113 parallel to folder arms 108 and 109, the ends of each link being pivotally secured at like positions on a pair of rotatable disks the axes of rotation of which are spaced apart a distance equal to the distance between the points of pivotal connection thereto of each link. Link 112 is thus mounted on similar disks 114 and 115, while link 113 is mounted on disks 116 and 117. Disks 114 and 116 are in turn secured to shafts 104 and 105 previously referred to, while disks 115 and 117 are likewise mounted on shafts 118 and 119, respectively, which are also journaled in brackets 106 and 107, parallel to and spaced from shafts 104 and 105.

Shafts 118, 119, 104, and 105 are continuously driven from main driving shaft 47 through a pair of similar transmissions which include bevel gears 120, 121 fixed on shaft 47 on opposite sides of the center thereof, and bevel gears 122, 123 which are in engagement with gears 120, 121 and are mounted on suitable vertical stub shafts 124, 125. Shafts 124, 125 also carry spur gears 126, 127 which mesh with similar gears 128, 129 secured to shafts 130, 131 rotatably supported in suitable bearing bosses secured to side frames 16 and 17. Shafts 130, 131 also carry driving sprockets 132, 133 around which pass chains 134, 135, the latter also encircling driven sprockets 136, 137 which are secured to stub shafts 138, 139 also journaled in brackets 106 and 107. Idler sprockets 140, 141, adjustably mounted in brackets 142 secured to and extending inwardly from side frames 16 and 17, may be provided, if desired, for adjusting the tension of driving chains 134, 135. Each of shafts 138, 139 is also provided with an eccentric gear 143, 144 which meshes with a similar eccentric gear 145, 146, the latter being secured to shafts 118 and 119 upon which rotatable disks 115 and 117 are mounted. Shafts 118, 119 are also provided with spur gears 147, 148 which drive similar spur gears 149, 150 secured to shafts 104 and 105 through the medium of idler gears 151, 152 mounted on shafts 153, 154 suitably journaled in brackets 106 and 107.

By means of the driving transmissions just described, folder or creasing arms 108 and 109 are given a continuous, variable speed movement toward and away from one another transverse to the direction of movement of the cartons through the machine, the path of travel of each of said folder arms being substantially elliptical so that there is a component of said movement along the line of travel of said cartons as well as transverse thereto. The folder arms are so adjusted that when in their innermost position they are spaced apart a distance substantially equal to the width of spreader members 10 and 11 so that the liner top which is engaged therebetween while not tightly squeezed is yet sufficiently creased to make the first fold. The component of movement of the folder arms in the direction of travel of the liner top serves to prevent any dragging effect upon the paper of said top during the time that it is engaged between the folder arms. The vertical position of folder arms 108 and 109 is preferably just above the level of the score lines of

the carton top so that the first fold or crease is made substantially in this plane.

At the same time that flap guides 90 and 91 are putting down the rear end flap of a carton, and folder arms 108 and 109 are making the first fold or crease in the liner top, suitable mechanism carried by the said folder means is also operative to put down the front end flap of the carton. In the form shown, folder arm 109 carries mounted thereon a flap bending finger 155 which is pivoted on a stud 156 for swinging movement to the straight ahead position shown in Figs. 1a and 15a from a position at right angles thereto wherein the finger extends transversely inward from folder arm 109. This swinging movement about stud 156 is effected by the engagement of a cam roller 157 with a cam plate 158 which is secured to cross tie member 19'' and positioned in the line of travel of cam roller 157, the latter being mounted on flap bending finger 155 by a suitable arm 159. As folder arm 109 is given its oscillatory movement by disks 116 and 117, finger 155 is alternately swung about stud 156 by the engagement of cam roller 157 with cam plate 158. The configuration of cam plate 158 and the mounting of cam roller 157 with respect to finger 155 are such as to cooperate with the swinging movement of folder arm 109 so that when said folder starts its inward movement toward the opposite folder arm 108, roller 157 is out of contact with plate 158 and finger 155 is extended transversely inward, as by a suitable spring (not shown), so as to penetrate between the back of the front end flap of the carton and the front of the carton liner. Then, as the swinging movement of the folder arm 109 continues, cam roller 157 engages cam plate 158 and swings finger 155 forward so as to lower the front end flap of the carton to a substantially horizontal position in which it is maintained during the subsequent folding and sealing operations by means next to be described.

The front end flap lowering operation is completed just before the carton reaches the entrance to the fixed folding mechanism which is supported upon a pair of bottom plates 160 and 161, the latter being suitably suspended from cross tie members 19'' and 19''' of the machine frame and spaced apart a sufficient distance to allow free passage of the liner tops therebetween. Plates 160 and 161 not only serve to support the fixed folder mechanism, but also act as flap guides which hold down the carton flaps during the rest of the liner folding and sealing operations. Accordingly, it will be understood that finger 155 completes its swinging movement and lowers the front end flap of the carton below the level of plates 160 and 161 just before the carton reaches this position in its forward travel so that said flap will be caught under the plates and held down thereby.

Referring now to Fig. 15a, the operations which have been performed by the mechanism thus far described may be summarized as follows: A lined and filled carton open at the top is supplied to the receiving end of the machine by conveyor 29, is transferred by pusher member 31 onto the conveyor ways 25 of the carrier means, is engaged by a pusher member 20 of the continuously moving chain 22 and is advanced thereby forwardly through the machine. At this time the top of the carton is in substantially the condition shown in position I at the extreme right of Fig. 15a, with the liner top open and square and the carton end and side flaps upstanding. As the carrier means advances the carton beneath the combined pack-

ing and side flap spreading member 54, rotation of the latter on its shaft 48 packs the material in the liner below the score lines of the top of the carton and simultaneously spreads the side flaps of the carton so that the pointed ends 58 of flap guide rails 59 pass between the side flaps and the sides of the liner, move said flaps down to a substantially horizontal position and hold them there until the carton passes beneath plates 160 and 161 of the fixed folder mechanism.

The carton next passes below the liner spreading mechanism and the top of the liner is elongated in the direction of its travel by spreader members or brushes 70 and 71. As previously explained, these spreader members travel with the carton for a predetermined distance while front and rear end flaps are put down and the first fold is made. Accordingly, continued advance of the carton passes its top between the separated flap guides 90 and 91 and into position between continuously moving folder arms 108 and 109. As the rear flap passes guides 90 and 91, they are moved inwardly toward one another by the action of cams 101 and 102 and due to their curved construction force the rear flap backward and downward, bending it below the level of the score line. As folder arms 108 and 109 are moved together, finger 155 engages the back of the front end flap and, upon engagement of cam roller 157 with cam plate 158, is swung about its pivot so as to lower said front end flap below guide plates 160 and 161. At the same time, the inward movement of folder arms 108 and 109 engages the elongated liner top, still extended by spreader members 70 and 71, and urges the opposite sides of the liner toward each other to form a first fold or crease just above the level of the score lines of the carton top, as indicated in position II of the carton in Fig. 15a.

As first folder or creasing arms 108 and 109 separate and the carton continues to advance, the now vertical, collapsed portion of the liner top passes between a pair of suitable guide members 162 and 163 which are secured to the rear ends of plates 160 and 161 and provide an entrance to the fixed folder mechanism. As previously mentioned, plates 160 and 161 are suitably suspended from cross tie members 19" and 19'" a sufficient distance apart to allow the passage therebetween of the liner tops, and form the supporting structure for a plurality of fixed folder members which are so constructed as to fold the liner top over upon itself a plurality of times and thereby effectively close the liner and prevent leakage of its contents, therefrom.

As shown best in Figs. 5-11, the first set of fixed folders is formed by a pair of stepped blocks 164 and 165 secured in any suitable manner to base plates 160 and 161, respectively, a pair of similar, irregularly shaped folder plates 166 and 167 which are adapted to be secured to the top of block 164 and to project over a portion of the passageway 172 between said block and the opposite block 165 to form the horizontal folds, a pair of diagonal grooves 168 and 169 of varying depth formed in block 165, and a pair of similarly shaped deflecting plates 170 and 171 adapted to be secured to the top of block 165 and to extend over grooves 168 and 169 so as to deflect the edges of the liner top into said grooves to form the vertical folds. Blocks 164 and 165 each comprises a high and low portion, as shown best in Fig. 6, plates 166 and 170 and groove 168 being respectively secured to and formed in the high portions of said blocks, while plates 167 and 171 and groove 169 are respectively secured to and formed in the

lower portions. This stepped arrangement is provided in order to properly fold the liner top in a plurality of folds, the height of the upstanding portion of the top constantly decreasing as the successive folds are made.

Referring now to Figs. 15 and 15a in conjunction with Figs. 5-11, the progress of the liner top through the fixed folders may be followed step by step. In position III, the carton is passing between vertical guides 162 and 163 forming 10 the entrance to the fixed folder mechanism, the liner top is collapsed and vertical as the result of the operation of the first folders or creasing elements, and the forward end of the liner top has just entered the passageway 172 formed between 15 blocks 164 and 165. As the forward edge of the vertical liner top comes into contact with the diagonally slanting edge of folder plate 166 which crosses passageway 172, the second fold of the liner top is made, the upper portion thereof being bent over at right angles, or to a horizontal position, relative to the rest of the top, between the bottom surface of folder plate 166 and the upper surface of block 165. Fig. 7 shows how this fold is made. As the carton is advanced, and 20 while the now horizontal outer portion of the liner top is still under the overhanging edge of folder plate 166, the forward edge of said portion passes under deflection plate 170 and is started down into the shallow, outer end of diagonal groove 168. Groove 168 not only slants diagonally inward toward passageway 172 but also continually increases in depth so that continued 25 advance of the carton causes the outer end of the liner top to follow the curvilinear path formed by groove 168 and to be folded through another 30 90°, or to a substantially vertical position such as shown in position IV of Fig. 15. Fig. 8 shows how this fold is made. The fourth and fifth 35 folds are made by plates 167 and 171 and groove 40 169, as indicated in Figs. 9 and 10, in the same manner as the second and third folds are made except that the height of the folders is decreased by the stepped construction of blocks 164 and 165. The folds produced by these folders are as 45 shown in positions V and VI of Fig. 15.

Although a liner folded in this manner will effectively prevent leakage of the contents therefrom, it is preferable to also seal the folded portion of the liner so as to render the closure more 50 nearly moisture-proof. When the liner is made of waxed paper, or other self-sealing material, a suitable sealing mechanism may comprise a pair of heated members, such as rollers, between which the folded liner tops may be passed and 55 which will engage said liner tops with sufficient pressure so that when the wax of the liner is melted by the heat, the various thicknesses of the folded top will be pressed into intimate engagement with one another and sealed through 60 the medium of said wax. In the embodiment shown, the sealing means comprises a pair of rollers 173 and 174 located in a horizontal plane on opposite sides of passageway 172, and secured to and supported just above plates 160 and 161 65 by a pair of stub shafts 175 and 176 which are rotatably supported in suitable bearing brackets 177 secured to cross tie member 19''' of the machine framework.

Rollers 173 and 174 are constantly driven from 70 main drive shaft 47 at the same peripheral speed as the carton advancing means. As shown, the drive comprises a bevel gear 178 fixed to shaft 47 and meshing with a similar bevel gear 179 mounted on a stub shaft 180. Secured to shaft 75

180 is a gear 181 which meshes with a similar gear 182 mounted on a suitable stub shaft 183. Keyed to gear 182 is a driving sprocket 184 around which passes a chain 185, said chain also engaging a driven sprocket 186 secured to shaft 176 on which roller 174 is mounted. Although, if desired, roller 173 may be frictionally driven by contact with the liner top, it is preferable that this roller also be positively driven at the same speed as but in the opposite direction to the roller 174. For this purpose, shaft 176 is provided with a second sprocket 187 which, through a chain 188, drives a similar sprocket 189 secured to shaft 175. In order to reverse the direction of rotation of roller 173 with respect to roller 174, chain 188 does not encircle sprocket 189 but only engages it on one side thereof, thence passing around an idler sprocket 190 which may be adjustably mounted in a suitable bracket 191 secured to side frame 16.

Any suitable means may be provided for heating rollers 173 and 174, those in the form shown comprising a pair of heater blocks 192 and 193 secured to cross tie member 19''' and supported closely adjacent to the peripheries of rollers 173 and 174. Each heater block is provided with a suitable heating element, such as an electric resistance unit 194, secured to the underside of said block and provided with the proper electrical leads 195 connected to a suitable source of current. In order that the efficiency of the heat transfer from heater blocks 192 and 193 to rollers 173 and 174 may be maintained as high as possible, the blocks are made thicker than the rollers, as shown in Fig. 12, and are not only provided with curved surfaces 196 and 197, which closely surround the peripheral edges of the rollers, but also include underslung portions 198 and 199 which extend inwardly beneath a substantial portion of the rollers. With this construction, and by using the proper material for rollers 173 and 174 and heater blocks 192 and 193, the heat transferring efficiency, and hence the sealing efficiency of the rollers, may be maintained at a high standard.

If desired, the fixed folder members past which the liner tops travel before encountering sealing rollers 173 and 174 may also be heated. Accordingly, the present embodiment includes a plurality of heater elements 200 (Figs. 1 and 5-10) which may be suitably secured to the outer sides of folder blocks 164 and 165, and electrically connected to one another and to a suitable source of current by leads 201. By thus heating the folder blocks, as well as the sealing rollers, the accumulation of wax upon the folder elements is maintained at a minimum, the wax-impregnated paper of the liner tops is more easily folded and the folded portions tend more readily to maintain their positions due to this preliminary heating and the consequent tendency of adjacent thicknesses of the liner tops to adhere to one another.

After passing between sealing rolls 173 and 174, the now folded and heat sealed liner top projects vertically upward from the liner and carton as shown in position VI of Fig. 15, and suitable means must be provided for folding or flattening said liner top to a substantially horizontal position about on a level with the score lines of the carton flaps so that the latter may be folded in on top of the liner, and the carton itself may be sealed. For this purpose, the rear, or left as viewed in the figures, extremities of base plates 160 and 161 are provided with a final pair

of fixed folder members or plates 202 and 203. As shown, plate 202 has a horizontal portion 204 which rests on and is suitably secured to plate 160, and a folding or flattening portion 205 which is substantially vertical and coplanar with the inner edge of base plate 160 at its forward end but gradually and continually turns inward and downward over passageway 172 until, at its rear or left end, it is substantially horizontal and coplanar with portion 204. Plate or block 203 comprises a horizontal portion 206 which rests on top of and is secured to base plate 161, and a downwardly offset horizontal portion 207 which is disposed within a recess 208 formed in plate 161 and underlies flattening or folding portion 205 of folder block 202. Portion 207 of folder block 203 may be made as thin as desired, and is so located that as the vertical, folded and sealed liner top passes between folder blocks 202 and 203 it is gradually folded or flattened over on top of the liner to a horizontal position substantially level with the score lines of the carton top. After passing through this last folder, the liner top occupies substantially the position shown in position VII of Fig. 15, and the carton is ready to have its top flaps folded in and sealed to complete the package.

Since the material of the liner tops sometimes becomes caught in the curvilinear passageway which it follows in its travel through the fixed folders, suitable means may be provided for readily separating the opposite groups of folder blocks so that the jammed or torn material may be quickly removed therefrom. As indicated in Figs. 1 and 2, and shown best in Fig. 13, one of the base plates supporting the fixed folder mechanism, here shown as plate 160, is fixedly secured in position as by arms 209 which are suitably clamped and supported in brackets 210 secured to cross tie members 19'' and 19'''. In order that base plate 160 may be adjusted so that its inner edge lines up with the line of travel of the liner tops, arms 209 are provided with upturned portions 210 the inner faces of which are engaged by the heads of suitable jackscrews 211 threaded into brackets 210. The opposite base plate 161 is movably suspended from cross tie members 19'' and 19''' as by suitable supporting rods 212 the lower ends of which pass through transverse elongated slots formed in suitable supporting blocks 214 secured to the upper surface of plate 161, the lower extremities of rods 212 being provided with enlarged heads 215 engaging the undersides of blocks 214. Suitable resilient means, such as a spring 216 secured at its opposite ends in any desired manner to pins 217 and 218 mounted on plates 160 and 161, respectively, are then provided whereby plate 161 is normally urged toward plate 160 so as to bring the folder members carried by both plates into proper relationship to form the folds in the liner tops passing through passageway 172. The outer ends of the slots in blocks 214 limit the inward movement of plate 161 to the proper amount. To separate the folder blocks so as to remove material caught therebetween, it is only necessary to grasp pin 218 and move plate 161 and the folder mechanism carried thereby outwardly to the right as viewed in Fig. 13, away from the opposite folders.

From the last folder mechanism which flattens the folded and sealed liner top down substantially level with the top of the carton, the carton passes to the mechanism for folding in the front and rear end flaps prior to its passage into the

carton sealing apparatus. As shown in position VII of Fig. 15, the extremities of the flattened liner top at this time extend forwardly and rearwardly beyond the front and rear faces of the 5 carton and overlie portions of the front and rear end flaps, and means must therefore be provided for folding these extremities into the confines of the carton either independently of or at the same time that the end flaps are folded in. In the embodiment shown, suitable mechanism is provided 10 for engaging the top surface of the liner and the side flaps while the front and rear end flaps and the overlying extremities of the liner top are first struck upwardly toward a vertical position and 15 then positively folded inwardly and downwardly on top of the liner and within the carton.

As shown in Figs. 1, 2, and 14, side frame 16 is reduced in height forward of tie member 19''' and has secured thereto a box-like housing 219 20 provided with oppositely disposed side openings 220 and 221, in the top of which housing is suitably supported, as in a bearing boss 222, a vertical stub shaft 223. Shaft 223 is adapted to be driven in synchronism with the other elements 25 of the machine from main driving shaft 47, and to this end has secured to its upper extremity a sprocket 224 which is driven by a suitable chain 225 from a sprocket 226 fixed on a stub shaft 227 which is rotatably supported in a suitable bearing 30 member 228 mounted on cross tie member 19''' and adjustable relative thereto as by a jackscrew 229. Shaft 227 also carries a sprocket 230 which is driven by a chain 231 from a sprocket 232 secured to stub shaft 124, said shaft in turn being 35 driven from main driving shaft 47 through bevel gears 120 and 122 previously described. The tension of driving chain 225 may be suitably adjusted by a roller 233 supported in engagement with said chain by an arm 234 adjustably mounted on bearing boss 222.

Secured to the lower end of shaft 223 and rotatable therewith is an arm or link 235 having an elongated slot 236 adjacent its outer end. Arm 235 rotates beneath a fixed cam plate 237 45 secured to, or formed integrally with, the top of housing 219 and having a cam groove 238 formed therein. Extending through a slot 236, the length of which is substantially equal to the difference between the maximum and minimum 50 distances of cam groove 238 from the axis of shaft 223, and engaging cam groove 238, is a cam roller 239 suitably mounted on a slide 240 which is supported in a carriage 241 for movement transverse to the direction of travel of the carton 55 through the machine, said carriage being in turn mounted for sliding movement parallel to the direction of movement of the carton on a pair of rods or guides 242. With this construction, carriage 241 is given a forward and backward reciprocating movement parallel to the movement of the carton, while at the same time slide 240, which is carried bodily forward and backward by carriage 241, is also reciprocated inwardly and outwardly, or transverse to the direction of movement 60 of the carton. During this movement of slide 240, its ends extend outwardly through side openings 220 and 221 of housing 219. The direction of rotation of shaft 223 is counter-clockwise, as viewed in Fig. 1, so that slide 240 comes in 65 approaching the carton, travels with the carton for a predetermined distance, then moves outwardly away from the carton and returns for the next cycle.

70 Mounted on the underside of the inner end of

slide 240 is a bearing 243 (Figs. 14 and 15) in which is fixedly supported a shaft 244 the extremities of which extend forwardly and rearwardly beyond the sides of bearing 243 and slide 240. Freely mounted on shaft 244 by a pair of arms 245 which straddle the inner end of slide 240 is a pressure plate 246 which extends inwardly beyond the end of slide 240 and is adapted to be moved into engagement with the top of the folded liner while the front and rear end flaps and the 10 overlying extremities of the folded liner top are folded in. Pressure plate 246 is normally maintained in an upwardly directed angular position relative to slide 240 by any suitable means such as a coil spring 247 one end of which is secured 15 to one of arms 245 while the other end is fastened to a collar 248 secured to shaft 244. Mounted on one of arms 245 and projecting downwardly therefrom is a spindle 249 on the lower end of which is rotatably mounted a cam roller 250. As 20 slide 240 is moved inwardly toward a carton through opening 221 in the side of housing 219, cam roller 250 engages a fixed cam plate 251 suitably supported on side frame 16 as by a bracket 252, further inward movement of the 25 slide causing pressure plate 246 to be moved downwardly about shaft 244 as a pivot into engagement with the top of the folded liner and the side flaps of the carton, as shown in the broken lines of Fig. 14, so as to prevent upward movement thereof during the infolding of the front and rear end flaps.

Slide 240 also carries on its upper surface and at its inner end a bearing 253 in which is rotatably supported a shaft 254 the extremities of 35 which extend forwardly and rearwardly beyond the ends of said bearing and the sides of slide 240. Rigidly secured to each end of shaft 254 is a collar 255 which has secured thereto, or formed integrally therewith, a flap striking 40 finger 256, said fingers being adapted to engage the outer surfaces of the front and rear end flaps of the carton and to strike said flaps upwardly to a substantially vertical position. Shaft 254 is normally maintained in such a position that 45 fingers 256 extend downwardly therefrom and below the level of the positions of the front and rear end flaps by a suitable spring 257 one end of which is anchored in bearing 253 while the other end is secured to one of collars 255. Secured to the portion of shaft 254 between the other collar 255 and bearing 253 is an upwardly extending arm 258 on the end of which is rotatably mounted a cam roller 259. As slide 240 is 50 moved inwardly toward a carton and pressure plate 246 is moved downwardly on top of the liner top by the engagement of cam roller 250 with cam 251, cam roller 259 comes into engagement with a fixed cam plate 260 which may be suitably supported in position to be engaged by 55 said cam roller as by an inwardly extending supporting arm 261 suitably secured to the top of housing 219. As cam roller 259 engages cam plate 260, continued inward movement of slide 240 causes shaft 254 to be rotated within its bearing 253 so that fingers 256 are raised beneath the then substantially horizontal front and rear end flaps of the carton and strike said flaps and the overlying extremities of the folded liner top 60 upwardly to a substantially vertical position, as 70 indicated in the broken lines in Fig. 14 and in position VIII of the carton in Fig. 15. The end flaps are then in position to be engaged by the mechanism for folding them inwardly on top of the liner, and it will be understood that pressure 75

plate 246 and fingers 256 are withdrawn out of engagement with the carton in time for such folds to be made, due to the continuous movement imparted to slide 240 by the engagement of cam 5 roller 239 with cam groove 238.

As the carton continues to be advanced with the flaps and the folded and sealed liner top in the positions indicated at VIII in Fig. 15, the front end flap with its overlying extremity of the 10 liner top comes into engagement with the upwardly turned forward end of a fixed folder plate 262 which may form part of the carton sealing machine. It is evident that continued movement of the carton under fixed folder plate 262 will 15 turn the forward end flap and the forward extremity of the sealed liner inwardly and downwardly on top of the liner within the carton. At the same time that the front end flap is being engaged by fixed folder plate 262, the carton is 20 passing under suitable mechanism for kicking the rear end flap and its overlying extremity of the sealed liner top inwardly and downwardly on top of the liner so that said flap will also pass under and be held down by fixed folder 25 plate 262. In the form shown, a horizontally extending flap engaging arm 263 is secured to the lower end of an arm 264 which is in turn secured to a stub shaft 265 rotatably supported in the end of a bearing arm 266. Arm 266 is rigidly mounted 30 on a shaft 267 which is supported above and transverse to the line of travel of the cartons through the machine by suitable bearing brackets 268 secured to cross tie member 19". The location of bearing arm 266 on shaft 267 and the 35 length of flap engaging arm 263 are such that the latter extends transverse to and in position to engage the outer surfaces of the rear end flaps of the cartons and, when actuated by suitable mechanism next to be described, to kick said 40 flaps forward and downward so that they will pass under fixed folder plate 262.

In order that flap engaging arm 263 may perform its desired function, it is preferably given both a movement with the carton, during the 45 time that the flap is being kicked forward, and an additional movement relative to the carton to effect the movement of the flap. In order to impart the first mentioned movement to arm 263, shaft 267 has secured thereto at one end (the 50 near end as viewed in Fig. 2) a pinion 269 which is engaged by a rack 270 secured to, or formed integral with, a connecting rod 271 the opposite end of which is connected to one extremity of a bell crank 272 pivotally supported on side frame 55 16 as at 273. The other extremity of said bell crank carries a cam roller 274 (Figs. 1a and 2a) which is in engagement with the groove of a suitable cam member 275 secured to the end of main driving shaft 47 opposite to that on 60 which cam member 46 previously referred to is secured. Vertical movement of rack 270 out of engagement with pinion 269 is prevented by means of a roller 276 which is mounted on bearing bracket 268 and engages the top surface of 65 said rack during its reciprocating movements.

Through the connections thus described, shaft 267 is continuously oscillated swinging bearing arm 266 and flap engaging arm 263 in synchronism with the successive cartons as they pass below said mechanism and then returning said arms to the position shown in Figs. 1 and 2 ready for engagement with the next carton. During this bodily swinging movement of arms 266 and 263, the latter is also given an independent swinging 75 movement so as to kick the rear end flaps of the

cartons forward and under fixed folder plate 262. For this purpose, shaft 265 has secured to its end opposite arm 264 another arm 277 on the extremity of which is rotatably mounted a suitable cam roller 278. Cam roller 278 is continually urged into engagement with the underside of a suitably cut cam plate 279 adjustably secured to bearing bracket 268 as by a spring 280 one end of which is anchored to bearing arm 266 while the other end is secured in any suitable manner 10 to arm 277. As flap engaging arm 263 is swung bodily in synchronism with the carton by shaft 267 and its associated driving mechanism, engagement of cam roller 278 with cam plate 279 oscillates shaft 265 in its bearing and swings arm 15 263 downward so as to tuck the rear end flap under the upturned end of fixed folder plate 262.

After both of the front and rear end flaps have been folded in in the manner described and the carton moves forward under fixed folder plate 20 262, the advance of the carton may continue through any desired mechanism for gluing the side flaps and folding them in on top of the in-folded end flaps so as to seal the carton in the well known manner.

Although it is believed that the operation of the machine disclosed herein is apparent from the preceding description, the various operations which are performed thereby may be summarized as follows: Cartons provided with inner liners or 30 bags of any suitable material, such as wax-impregnated paper, open at the top and filled with any desired material, are continuously supplied to the receiving end of the machine from any suitable source, such as a filling and weighing 35 machine, by means of a continuously travelling conveyor 29. The lined and filled cartons thus supplied to the machine are then transferred laterally one by one by a pusher member 31 to a continuously moving carrier mechanism which 40 extends the entire length of the machine. The reciprocation of pusher member 31, as well as the movements of all of the other elements of the machine which act upon the cartons and their liners, are synchronized with those of the carrier 45 means by virtue of the fact that all of said elements derive their motion from a main driving shaft 47 which in turn may be driven by or drive the mechanism which actuates the carrier means.

Upon transfer to the carrier means, each carton is engaged by a continuously moving pusher member 20 and is constantly advanced thereby through the machine. The carton with its vertically upstanding liner and carton flaps first passes under a combined packing and flap spreading member 54, the body portion 55 of which penetrates into the open liner top and packs the material therein below the score lines of the top of the carton, while a pair of flap bending guides 57 engage the inner surfaces of the sides of the 60 liner top and exert an outward pressure thereagainst whereby the side flaps of the carton are bent outwardly so as to permit the pointed ends 58 of guide rails 59 to penetrate between the side flaps and the sides of the liner, and to put and 65 hold the side flaps down in a substantially horizontal position.

Further advance of the carton brings it beneath the liner spreading mechanism, and spreader members 70 and 71 of one of carriers 69 extend into the open liner top and by engagement of cam rollers 85 and 87 with cam members 84 and 89, respectively, are spread apart or separated so as to spread or elongate the liner top in the direction of movement of the carton. At

the same time, continuously moving flap bending guides 90 and 91 move inwardly to engage the rear end flap and force it down to a horizontal position. While the liner top is still engaged by spreader members 70 and 71, first folder or creasing arms 108 and 109 are moved toward one another transversely to the direction of movement of the carton and engage the elongated liner top therebetween so as to form a crease or first fold therein substantially at the level of the score lines of the carton top. Simultaneously with the making of this crease or first fold, the forward end flap of the carton is put down beneath plates 160 and 161 by the swinging movement of finger 155 caused by the engagement of cam roller 157 with cam plate 158.

Due to the parallel motion mounting of the first folder or creasing members on rotating disks 114, 115, 116 and 117, the folder members travel in a substantially elliptical path so that they have movement not only transverse to the direction of movement of the carton but also in the same direction. The drive for said members is also suitably designed so that their movement in the same direction as the cartons is at the same speed as the cartons during the time that folder arms 108 and 109 are in engagement with the liner top thereby avoiding any possibility of tearing or mutilation of the liner. This first fold or crease is made without any effort to positively apply pressure to or seal the liner top and is for the purpose of preparing the liner top for the subsequent folding or doubling over thereof.

Leaving the first folder or creasing mechanism, the carton flaps and liner top are substantially horizontal and vertical, respectively, as indicated at position II in Fig. 15a, and continued advance of the carton moves the liner top between guides 162 and 163 into passageway 172 between the opposing groups of fixed folder members. As the liner top is moved through the fixed folder mechanism, it follows a curvilinear path and is folded over upon itself a plurality of times by the co-operative action of folder plates 166 and 167, deflector plates 170 and 171, and grooves 168 and 169, the successive folds being clearly indicated in positions III, IV, V, and VI of Figs. 15 and 15a. If desired, these fixed folders may be provided with suitable heating means both to prevent the accumulation of wax thereon and to facilitate the folding and sealing of the liner tops.

From the first set of fixed folders, the now vertical folded liner top is carried between sealing rollers 173 and 174 which press the elements of the folded liner top together, and, through the medium of the heat which is transmitted to the rollers from heater blocks 192 and 193, completely seal said liner top by the melting of the wax or other adhesive with which the paper of the liner is treated. Further advance of the carton moves the now folded and sealed liner top between the final pair of fixed folders 202 and 203 which flatten the liner top down to a horizontal position substantially level with the score lines of the carton, as shown in position VII of Fig. 15.

The carton then moves past the mechanism which first strikes up and then folds in the front and rear end flaps of the carton preparatory to the final closing and sealing of the carton top. At this point, slide 240 is moved inwardly toward and at the same time forwardly with the carton, and when cam roller 250 engages cam plate 251, pressure plate 246 is lowered into engagement with the folded and flattened liner top and the side flaps of the carton. Continued movement of

slide 240 brings cam roller 259 into engagement with cam plate 260 so that flap striking fingers 256 are thrown upwardly, engaging the outer surfaces of the front and rear end flaps and kicking them and their overlying extremities of the folded liner top upwardly to a substantially vertical position, as shown at VIII in Fig. 15. As the carton advances further, the now substantially vertical front end flap is engaged by, and moved inwardly and downwardly by, the upturned end of fixed folder plate 262, while at the same time finger 263 is swung into engagement with the outer surface of the rear end flap by the oscillation of shaft 267 and by movement of cam roller 278 along cam plate 279 is moved so as to kick said flap forwardly and downwardly in time to catch beneath the end of fixed folder plate 262. From this position the carton continues its advance through any desired form of carton sealing machine wherein the side flaps are folded in on top of the end flaps and the folded and sealed liner top, and are sealed in any suitable manner so as to form the completed carton with its folded and sealed liner.

There is thus provided by the present invention a new and improved machine for folding and sealing the top of the liner or bag of a lined carton prior to the closing and sealing of the carton itself. The novel mechanism herein disclosed is automatic in operation and continuously folds and seals in a rapid and efficient manner the liner tops of a succession of cartons as they are continuously advanced through the machine. The liner tops are first given a plurality of folds which are of themselves sufficient to make the liner sift-proof, and then the already folded portion is tightly sealed so as to make it more nearly moisture-proof. In order that the folding and sealing of the liner top may be performed efficiently and rapidly, novel means are also provided for spreading and putting down the flaps of the carton so that they will not interfere with the operation of the folding means, while the liner itself is preliminarily spread or elongated in the direction of movement so that the folds are more easily made. The first fold or crease is made by a pair of continuously moving folder arms one of which also carries the means for putting down one of the end flaps of the carton, while a plurality of novelty formed fixed folder blocks or plates have been provided for making a plurality of subsequent folds. After the folded liner tops have been sealed by rotatable sealing members which are heated in a novel manner, new and improved means have been provided for flattening the folded and sealed portion of the liner down on top of the liner. Continuously movable means of novel construction have also been included for folding in the end flaps of the carton prior to the closing and sealing thereof. All of the novel elements of the machine herein disclosed are synchronized in their movements and cooperate in an efficient manner to produce a unitary, high speed machine for handling, closing and sealing a lined carton.

It will be obvious that the invention is not limited to the form shown in the drawings but is capable of a variety of mechanical embodiments. For example, any of the numerous motion producing mechanisms described may be replaced with equivalent arrangements capable of achieving the same result, and any suitable type of conveyor or carrier means may obviously be employed in place of the well known means illustrated. Moreover, although the apparatus has

been described as adapted for connection to a carton sealing machine so that the movement of the cartons is continuous therethrough, it will be understood that the mechanism constituting the present invention may also be used independently, or in combination with any other desired form of apparatus. Also, while the liner sealing elements have been described as suitable for a liner made of material which is self-sealing, such as wax-impregnated paper, it will be understood that cellophane, glassine or any other suitable lining paper can be handled in accordance with the present invention by inserting suitable gluing devices at any desired point in the machine and eliminating the heating of rollers 173 and 174 and of the fixed folder blocks. It is also apparent that, if desired, the heat sealing or suggested gluing devices may both be omitted, and the tops of the liners merely folded into position without sealing, and that any desired number of folds may be made by the fixed folder mechanism, the invention not being limited to the number shown. Furthermore, any of the various elements of the machine may be used independently of the others, and various combinations can be made of the several features illustrated and described, within the present invention. Various other changes, which will now appear to those skilled in the art, may be made in the form, details of construction and arrangement of the parts without departing from the spirit of the invention, and reference is therefore to be had to the appended claims for a definition of the limits of the invention.

What is claimed is:

35 1. In a machine for sealing cartons having inner liners, carrier means for advancing the cartons through said machine, means for spreading the liner tops in the direction of movement of said carrier means, means movable transversely to the direction of movement of said carrier means for moving the opposite sides of the liner tops toward one another to form relatively flat, upstanding foldable portions therein, a plurality of fixed folder members between which said portions of the liner tops are moved, said members being so shaped as to form a plurality of folds in said liner tops, and means for sealing said folded liner tops.

2. In a machine for sealing cartons having inner liners, carrier means for continuously advancing the cartons through said machine, means for spreading the liner tops in the direction of movement of said carrier means, means including a pair of arms disposed on opposite sides of the path of travel of the liner tops and movable together transversely to the direction of movement of said carrier means for moving the opposite sides of the liner tops toward one another to form relatively flat, upstanding foldable portions therein, a plurality of fixed folder members between which portions of the liner tops are moved, said members being so shaped as to form a plurality of folds in said liner tops, and a pair of heated sealing members between which said folded liner tops are moved to seal the same.

3. In a machine for sealing cartons having inner liners, carrier means for advancing the cartons through said machine, means for spreading the liner tops in the direction of movement of said carrier means, means movable transversely to the direction of movement of said carrier means for moving the opposite sides of the liner tops toward one another to form relatively flat, upstanding foldable portions therein, a plurality of fixed folder members between which said

portions of the liner tops are moved, said members being so shaped as to form a plurality of folds in said liner tops, means for sealing said folded liner tops, and additional folder members for flattening the sealed and folded liner tops 5 to a substantially horizontal position.

4. In a machine for sealing cartons having inner liners, carrier means for continuously advancing the cartons through said machine, means for spreading the liner tops in the direction of 10 movement of said carrier means, means including a pair of arms disposed on opposite sides of the path of travel of the liner tops and movable together transversely to the direction of movement of said carrier means for moving the opposite 15 sides of the liner tops toward one another to form relatively flat, upstanding foldable portions therein, a plurality of fixed folder members between which said portions of the liner tops are moved, said members being so shaped as to form 20 a plurality of folds in said liner tops, a pair of heated sealing members between which said folded liner tops are moved to seal the same, and additional folder members for flattening the sealed and folded liner tops to a substantially 25 horizontal position.

5. In a machine for sealing cartons having inner liners, carrier means for continuously advancing the cartons through said machine, means for spreading the liner tops in the direction of 30 movement of said carrier means, means for moving the opposite sides of the liner tops toward one another while engaged by said spreading means and thereby forming relatively flat, upstanding foldable portions therein, a plurality of 35 fixed folder members between which said portions of the liner tops are moved, said members being so shaped as to form a plurality of folds in said liner tops, means for sealing said folder liner tops, additional folder members for flattening the sealed and folded liner tops, to a substantially 40 horizontal position, and means for folding in the flaps of said cartons on top of said sealed and folded liner tops.

6. In a machine for sealing cartons having 45 inner liners, carrier means for continuously advancing the cartons through said machine, means for spreading the liner tops in the direction of movement of said carrier means, means including a pair of arms disposed on opposite sides of 50 the path of travel of the liner tops and movable together transversely to the direction of movement of said carrier means for moving the opposite sides of the liner tops toward one another at substantially the level of the carton flaps and 55 thereby forming relatively flat, upstanding foldable portions therein, a plurality of fixed folder blocks between which said portions of the liner tops are moved, said blocks being so shaped as to form a plurality of folds in said liner tops, a 60 pair of heated sealing rolls between which said folded liner tops are moved to seal the same, additional folder blocks for flattening the sealed and folded liner tops to substantially the level of the score lines of said carton flaps, and means for 65 folding in the flaps of said cartons on top of said sealed and folded liner tops.

7. In a machine for sealing cartons having inner liners, carrier means for continuously advancing the cartons through said machine, means 70 for spreading the side flaps of said cartons, means for spreading the liner tops in the direction of movement of said carrier means, means for spreading and putting down the end flaps of the cartons, and means movable transversely to the 75

- direction of movement of said carrier means for moving the opposite sides of the liner tops toward one another at substantially the level of the carton flaps and thereby forming relatively flat, upstanding foldable portions therein, said liner top spreading means travelling with the cartons during the operation of said last two mentioned means.
8. In a machine for sealing cartons having inner liners, carrier means for continuously advancing the cartons through said machine, means for spreading the liner tops in the direction of movement of said carrier means, and means movable transversely to the direction of movement of said carrier means for moving the opposite sides of the liner tops toward one another and thereby forming relatively flat, upstanding foldable portions therein, said liner top spreading means travelling with the cartons during the operation of said last mentioned means.
9. In a machine for sealing cartons having inner liners, carrier means for continuously advancing the cartons through said machine, means for spreading the liner tops in the direction of movement of said carrier means, means for pressing the opposite sides of said liner tops toward one another to form relatively flat, upstanding foldable portions therein, said liner top spreading means travelling with the cartons during the operation of said last mentioned means, and a plurality of fixed folder blocks between which said portions of the liner tops are moved, said blocks being so shaped as to form a plurality of folds in said liner tops as the latter are moved therebetween.
10. In a machine for sealing cartons having inner liners, carrier means for continuously advancing the cartons through said machine, means for spreading the side flaps of said cartons, means for spreading the liner tops in the direction of movement of said carrier means, means for spreading and putting down the end flaps of the cartons, means movable transversely to the direction of movement of said carrier means for moving the opposite sides of the liner tops toward one another at substantially the level of the carton flaps and thereby forming relatively flat, upstanding foldable portions therein, said liner top spreading means travelling with the cartons during the operations of said last two mentioned means, a plurality of fixed folder members between which said portions of the liner tops are moved, said members being so shaped as to form a plurality of folds in said liner tops as the latter are moved therebetween, and means for heat sealing said folded liner tops.
11. In a machine for sealing cartons having inner liners, carrier means for continuously advancing the cartons through said machine, means for spreading the side flaps of said cartons, means for spreading the liner tops in the direction of movement of said carrier means, means for spreading and putting down the end flaps of the cartons, means including a pair of arms disposed on opposite sides of the path of travel of the liner tops and movable together transversely to the direction of movement of said carrier means for moving the opposite sides of the liner tops toward one another at substantially the level of the carton flaps and thereby forming relatively flat, upstanding foldable portions therein, a plurality of fixed folder blocks between which said portions of the liner tops are moved, said blocks being so shaped as to form a plurality of folds in said liner tops, a pair of heated sealing rolls between which said folded liner tops are moved to seal the same, and additional folder blocks for flattening the sealed and folded liner tops to substantially the level of the score lines of said carton flaps.
12. In a machine for sealing cartons having filled inner liners, carrier means for continuously advancing the cartons through said machine, means for packing the material in the liners below the score lines of the carton flaps and for simultaneously spreading the side flaps thereof, means for spreading the liner tops in the direction of movement of said carrier means, means for spreading and putting down the end flaps of the cartons, and means for moving the opposite sides of the liner tops toward one another at substantially the level of the carton flaps, thereby forming relatively flat, upstanding foldable portions therein.
13. In a machine for sealing cartons having filled inner liners, carrier means for continuously advancing the cartons through said machine, means for packing the material in the liners below the score lines of the carton flaps and for simultaneously spreading the side flaps thereof, means for spreading the liner tops in the direction of movement of said carrier means, means for spreading and putting down the end flaps of the cartons, means movable transversely to the direction of movement of the carrier means for moving the opposite sides of the liner tops toward one another to flatten the same while the latter are engaged by said spreading means, and a plurality of fixed folder members between which said flattened liner tops are moved, said members being so shaped as to form a plurality of folds in said liner tops as the latter are moved therebetween.
14. In a machine for sealing cartons having filled inner liners, carrier means for continuously advancing the cartons through said machine, means for packing the material in the liners below the score lines of the carton flaps and for simultaneously spreading the side flaps thereof, means for spreading the liner tops in the direction of movement of said carrier means, means for spreading and putting down the end flaps of the cartons, means including a pair of arms disposed on opposite sides of the path of travel of the liner tops and movable together transversely to the direction of movement of the carrier means for moving the opposite sides of the liner tops toward one another at substantially the level of the carton flaps and thereby forming relatively flat, upstanding foldable portions therein, a plurality of fixed folder blocks between which said portions of the liner tops are moved, said blocks being so shaped as to form a plurality of folds in said liner tops, a pair of heated sealing rolls between which said folded liner tops are moved to seal the same, and additional folder blocks for flattening the sealed and folded liner tops to substantially the level of the score lines of said carton flaps.
15. In a machine for sealing cartons having inner liners, conveyor means for delivering filled cartons open at the top to the receiving end of said machine, carrier means for advancing the cartons through said machine, means for transferring the cartons from said conveyor means to said carrier means, means for packing the ma-

terial in the liners below the score lines of the carton flaps and for simultaneously spreading the side flaps thereof, means for spreading the liner tops in the direction of movement of said carrier means, means movable transversely to the direction of movement of said carrier means for moving the opposite sides of the liner tops toward one another at substantially the level of the carton flaps and thereby forming relatively flat, upstanding foldable portions therein, said liner top spreading means travelling with the cartons during the operation of said last mentioned means, a plurality of fixed folder members between which said portions of the liner tops are moved, said members being so shaped as to form a plurality of folds in said liner tops, a pair of heated sealing rolls between which said folded liner tops are moved to seal the same, additional folder members for flattening the sealed and folded liner tops to substantially the level of the score lines of said carton flaps, and means for folding in the flaps of said cartons on top of said sealed and folded liner tops.

16. In a machine for sealing cartons having inner liners, conveyor means for delivering filled cartons open at the top to the receiving end of said machine, carrier means for continuously advancing the cartons through said machine, means for transferring the cartons from said conveyor means to said carrier means, means for packing the material in the liners below the score lines of the carton flaps and for simultaneously spreading the side flaps thereof, means for spreading the liner tops in the direction of movement of said carrier means, means for spreading and putting down the end flaps of the cartons, means including a pair of arms disposed on opposite sides of the path of travel of the liner tops and movable together transversely to the direction of movement of said carrier means for moving the opposite sides of the liner tops toward one another at substantially the level of the carton flaps and thereby forming relatively flat, upstanding foldable portions therein, a plurality of fixed folder blocks between which said portions of the liner tops are moved, said blocks being so shaped as to form a plurality of folds in said liner tops, a pair of heated sealing members between which said folded liner tops are moved to seal the same, additional folder blocks for flattening the sealed and folded liner tops to substantially the level of the score lines of said carton flaps, and means for folding in the flaps of said cartons on top of said sealed and folded liner tops.

17. In a machine for closing the inner liners of lined cartons, carrier means for delivering lined and filled cartons open at the top to the receiving end of said machine and for advancing said cartons therethrough, and means positioned above said carrier means for spreading the liner tops in the direction of movement of said carrier means preparatory to the closing thereof, said liner top spreading means travelling with the cartons for a predetermined distance.

18. In a machine for closing the inner liners of lined cartons, carrier means for delivering lined and filled cartons open at the top to the receiving end of said machine and for advancing said cartons therethrough, and means positioned above said carrier means for spreading the liner tops in the direction of movement of said carrier means preparatory to the closing thereof, said liner top spreading means including a travelling carrier movable parallel to and in synchronism with the cartons during a portion of the travel

of the latter, a pair of spreader members mounted on said carrier and adapted to enter said open liner tops, and means for separating said members after they have entered said liner tops.

19. In a machine for closing the inner liners of lined cartons, carrier means for delivering lined and filled cartons open at the top to the receiving end of said machine and for continuously advancing said cartons therethrough, and means positioned above said carrier means for spreading the liner tops in the direction of movement of said carrier means preparatory to the closing thereof, said liner top spreading means including a movable carrier travelling closely adjacent to and at the same speed as the cartons for a predetermined distance, a pair of spreader members pivotally mounted on said carrier and adapted to project into the open tops of said liners, and cam-actuated means for moving said members away from each other after they have entered said liner tops.

20. In a machine for folding and sealing the inner liners of lined cartons, carrier means for continuously advancing lined and filled cartons open at the top through said machine, a plurality of fixed folder members spaced along the line of travel of said carrier means and in position to engage and fold the tops of said liners in a plurality of over-and-over folds, and a pair of heated sealing rolls between which said folded liner tops are moved to seal the same.

21. In a machine for folding and sealing the inner liners of lined cartons, carrier means for continuously advancing lined and filled cartons open at the top through said machine, a plurality of folder members spaced along the line of travel of said carrier means and in position to engage and fold the tops of said liners in a plurality of folds, a pair of sealing rolls between which said folded liner tops are moved to seal the same, and means for heating both said folder members and said sealing rolls.

22. In a machine for closing and folding the inner liners of lined cartons, carrier means for advancing lined and filled cartons open at the top through said machine, means for elongating the liner tops in the direction of movement of said carrier means, means for closing and creasing the elongated liner tops, and a plurality of fixed folder members having a curvilinear passageway formed therein through which said closed and creased liner tops are moved to form a plurality of over-and-over folds therein.

23. In a machine for folding and sealing the inner liners of lined cartons, carrier means for advancing lined and filled cartons open at the top through said machine, means for elongating the liner tops in the direction of movement of said carrier means, means for closing and creasing the elongated liner tops, a plurality of fixed folder members having a curvilinear passageway formed therein through which said closed and creased liner tops are moved to form a plurality of over-and-over folds therein, and means for sealing the folded liner tops.

24. In a machine for folding and sealing the inner liners of lined cartons, carrier means for continuously advancing lined and filled cartons open at the top through said machine, means for elongating the liner tops in the direction of movement of said carrier means, means for closing and creasing the elongated liner tops, a plurality of fixed folder blocks having a curvilinear passageway formed therein through which said closed and creased liner tops are moved to form

- a plurality of over-and-over folds therein, a pair of sealing rolls between which said folded liner tops are moved after leaving said folder blocks to seal the same, and means for heating both said 5 fixed folder blocks and said pair of sealing rolls.
25. In a machine for folding and sealing the inner liners of lined cartons, carrier means for continuously advancing lined and filled cartons open at the top through said machine, a plurality of fixed folder members spaced along the line of travel of said carrier means and in position to engage and fold the tops of said liners in a plurality of over-and-over folds, said folded liner tops being substantially vertical after passage 10 through said folder members, a pair of heated sealing rolls between which said substantially vertical folded liner tops are moved to seal the same, and additional folder members for flattening said sealed and folded liner tops to a substantially horizontal position.
26. In a machine for folding and sealing the inner liners of lined cartons, carrier means for continuously advancing lined cartons open at the top through said machine, a pair of folder 15 members disposed on opposite sides of the path of travel of said liner tops and movable substantially transversely to the direction of movement of said carrier means to flatten the open liner tops therebetween, and means carried by one of said folder members for putting down the forward end flaps of said cartons.
27. In a machine for folding and sealing the inner liners of lined cartons, carrier means for continuously advancing lined cartons open at the top through said machine, a pair of folder members disposed on opposite sides of the path of travel of said liner tops and movable substantially transversely to the direction of movement of said carrier means to flatten the open liner 20 tops therebetween, and a cam-operated finger carried by one of said folder members for putting down the forward end flaps of said cartons.
28. In a machine for sealing a carton having an inner liner, carrier means for continuously advancing a lined and filled carton through said machine, means for folding the top of said liner, means for putting down certain of the flaps of said carton into a substantially horizontal plane and for maintaining said flaps in said position during said liner folding operations, means for striking said flaps upwardly to a substantially vertical position after said liner folding operations have been completed, means for holding 45 said carton against upward displacement during operation of said flap striking means, and means for folding said substantially vertical flaps inwardly and downwardly on top of said folded liner.
29. In a machine for handling cartons having inner liners, carrier means for advancing the cartons through said machine, means for elongating the liner tops in the direction of movement of said carrier means, means for closing and 50 creasing the elongated liner tops, means for moving said elongating means in synchronism with said carrier means during a portion of the travel of the latter, said closing and creasing means being effective to close and crease the elongated liner tops during said same portion of the travel of said carrier means, and a plurality of fixed folder members between which said closed and 55 creased liner tops are moved, said members being so shaped as to form a plurality of over-and-over

60 folds in said closed and creased liner tops as the latter are moved therebetween.

30. In a machine for handling cartons having inner liners, carrier means for advancing the cartons through said machine, means for elongating the liner tops in the direction of movement of said carrier means, means for closing and creasing the elongated liner tops, a plurality of fixed folder members between which said closed and creased liner tops are moved, said members being so shaped as to form a plurality of over-and-over 10 folds in said liner tops as the latter are moved therebetween, and pressure roll means between which the folded liner tops are moved upon emerging from between said fixed folder members.

31. In a machine for sealing a carton having an inner liner, carrier means for advancing a lined and filled carton through said machine, means for closing and folding the top of said liner, means for putting down certain of the flaps of said carton into a substantially horizontal plane and for maintaining said flaps in said position during the liner closing and folding operations, and means operative after said flaps have been 15 released by said last named means for striking said flaps upwardly to substantially vertical positions comprising a holding down member, means for moving said member into engagement with said folded liner top to prevent upward movement 20 of the carton relative to said carrier means, striking fingers normally positioned below the level of said carton flaps, and means for moving said fingers upwardly and into engagement with the outer surfaces of said flaps whereby the latter are struck upwardly to substantially vertical positions.

32. In a machine for sealing a carton having an inner liner, carrier means for advancing a lined and filled carton through said machine, means for closing and folding the top of said liner, means for putting down certain of the flaps of said carton into a substantially horizontal plane and for maintaining said flaps in said position during the liner closing and folding operations, and means operative after said flaps have been released by said last named means for striking said flaps upwardly to substantially vertical positions comprising a slide member movable in synchronism with said carrier means, a holding down member carried 40 by said slide member, means for moving said holding down member into engagement with said folded liner top to prevent upward movement of the carton relative to said carrier means, a plurality of striking fingers also carried by said 45 slide member and normally positioned below the level of said carton flaps, and means for moving said fingers upwardly and into engagement with the outer surfaces of said flaps whereby the latter are struck upwardly to substantially vertical positions.

33. In a machine for sealing a carton having an inner liner, carrier means for continuously advancing a lined and filled carton through said machine, means for folding the top of said liner, means for putting down the front and rear flaps of said carton into substantially horizontal positions, means for maintaining said flaps in said positions during said liner closing operation, means including a pair of striking fingers for positively moving said flaps upwardly to substantially vertical positions after said liner folding operation has been completed, and means for folding said substantially vertical flaps inwardly and downwardly on top of said folded liner.

34. In a machine for handling cartons having inner liners, carrier means for advancing the lined cartons through said machine, means for providing each of said liners with a closed substantially vertical top portion, folder means fixed in the path of travel of said closed vertical liner tops for forming a plurality of over-and-over folds therein, and pressure roll means between which said folded liner tops are moved to compress and crease said folds.
35. In a machine for handling cartons having inner liners, the combination of carrier means for advancing the cartons through the machine, means for elongating the liner tops in the direction of movement of said carrier means, means for straightening the sides of the elongated liner tops to substantially vertical position and for bringing said sides closely adjacent one another, and means for folding said elongated and straightened liner tops to close the same.
36. In a machine for handling cartons having inner liners, the combination of carrier means for advancing the cartons through the machine, means for elongating the liner tops in the direction of movement of said carrier means, means for straightening the sides of the elongated liner tops to substantially vertical position and for bringing said sides closely adjacent one another, and means fixed in the path of travel of said elongated and straightened liner tops for folding the same over upon themselves to close the liners.

CHARLES F. RICHARD.
